UNITED STATES PATENT OFFICE

ROY L. MILLS, OF CHICAGO, ILLINOIS

ABSORPTION FIN

Application filed April 3, 1931. Serial No. 527,502.

The present invention relates to absorption fins and particularly to a construction of shells for defining the combustion chambers of heaters wherein the fins are incorporated whereby extreme and sudden changes of temperature may take place without damage to the heaters.

The term "heater" is herein used generally and not by way of limitation and includes stoves, furnaces, boilers and all like apparatus.

Heaters are usually constructed with cast iron or cast steel parts forming the combustion chambers and with metal parts of sheet iron, sheet steel and even castings and the like about the combustion chambers for providing the compartments or spaces for the heat conveying elements such as air, water and the like. It is well known that expansion and contraction occurs in all heaters in accordance with the amount of heat generated in the combustion chambers, and where amount of heat varies the expansion and contraction occur with the result that some of the heater parts become distorted, warped, and oftentimes cracked, thus becoming useless for efficient heating purposes and requiring replacement.

This is especially true where the heaters are utilized with intermittent fire such as in oil burners and gas fired heater wherein the oil or gas fire is on for awhile and off for awhile. The parts therefore are constantly contracting and expanding with the result that an ordinary heater quickly becomes useless for efficient heating purposes.

The present invention is directed to the construction of heaters employing absorption fins for the combustion chambers whereby temperature changes over a wide range may be had without unduly warping, distorting or straining the heaters, thereby lengthening the lives of such heaters to a marked extent.

An object of the present invention is to provide a shell for defining the combustion chamber of a heater which shell is formed with plaits at intervals, which plaits are closed and opened under expansion and contraction of the shell due to temperature

changes. The provision of these plaits enables expansion of the shell under high temperature conditions to a marked extent and allowing contraction thereof when the heat is stopped without distortion, warping or strain. The plaits open and close with something like pincers action during contraction and expansion. Furthermore, the heat-conveying elements such as air, water and the like pass upwardly along the outside of the shell and plaits whereby the heat within the combustion chamber is radiated to such heat conveying elements.

The invention is especially useful in connection with intermittent fires such as oil- 65 burners and gas-fired heaters.

An object of the present invention is to provide a heater construction wherein expansion and contraction of the heater parts may be large due to a wide range of temperature variations without causing warping, distortion or damage to the heater.

Another object of the invention is to provide absorption fins for use with heaters whereby considerable amount of expansion 75 and contraction of the heater parts may take place without damage to the heater, thus prolonging the life of the heater and of the materials of which it is constructed.

Another object of the invention is to provide a shell for the combustion chambers of heaters which shell is formed with a plurality of plaits which are formed as substantially radially arranged vertically disposed fins extending outwardly from the combustion chamber and with pockets opening into the combustion chamber whereby maximum radiating surface is presented to the heat conveying element.

Another object of the invention is to provide a shell for defining the combustion chambers of heaters which shell is provided with a plurality of plaits which plaits have opening and closing movements due to the expansion and contraction of the shell in use, 90 because of temperature variations thereby prolonging the life of the heater and the shell.

A still further object of the invention is to provide a shell for forming the combus- 100

tion chamber of a heater with a fin having bellows-like action during expansion and contraction of the shell.

A still further object of the invention is to provide a combustion chamber shell for heaters which shell is provided with absorption fins so that portions of the shell may have expansion and contraction movement over a wide range due to temperature changes without damage to the shell.

Another and further object of the invention is to provide a heater so constructed that extremes of temperature may be imposed without unduly warping, distorting or straining the heater and whereby the heater may be useful in effecting rapid changes of temperature in the heat conveying medium or element.

Another and further object of the invention is to provide a shell for the combustion chamber of a heater which shell is formed with absorption fins which readily expand and contract with the temperature changes within the combustion chamber and wherein a breathing or bellows-like action takes place during expansion and contraction.

A still further object of the invention is to provide absorption fins for heaters which are formed as substantially radially arranged vertically disposed fins extending outwardly from the combustion chamber shell and which fins form pockets which open and close under expansion and contraction of the shell due to temperature variations.

A yet further object of the invention is to provide an efficient and simple heater for effecting quick temperature changes in heating mediums over a wide range and wherein such temperature changes are effected without harm to the heater.

Generally speaking the invention contemplates a shell for a combustion chamber of a heater which is formed from relatively thin sheet metal provided with absorption fins such as plaits struck outwardly from the inner surface of the shell. The plaits tending to open and close during contraction and expansion of the shell in use and the outsides of which plaits form passages whereby the heating medium is passed for heat radiating purposes.

The invention further contemplates the formation of such plaits from sheet metal which plaits have the tops and bottoms of the openings or slots closed and with the intermediate part of the slots of slightly greater width normally than any other part whereby maximum expansion and contraction may take place without damage to the shell or other parts of the heater.

The above, other and further objects of the invention will be apparent from the following description, accompanying drawing and appended claims.

The present invention may be embodied

in almost any type of heater but finds especial use in connection with heaters which are intermittently fired, such as oil and gas burners and the form of apparatus chosen to exemplify the present invention is illustrated as a heater suitable for installation in a garage whereby air serves as the heat conveying medium.

The accompanying drawing illustrates a hot air heater suitable for use in garages fired by oil, and the views thereof are as follows:

Figure 1 is a vertical sectional view through the illustrated type of heater.

Figure 2 is an enlarged horizontal sectional view taken substantially in the plane of line II-II of Figure 1.

Figure 3 is an enlarged front elevational view of a fragmental portion of the shell showing the expansion slot formed by a plait of the present invention.

Figure 4 is an enlarged fragmental sectional view of two of the plaits as the same appear when installed in the illustrated form of heater.

Figure 5 is a top plan view of the illustrated form of heater.

The drawing will now be explained.

The form of heater chosen to exemplify the present invention is one for heating hot air by means of an oil burner and as illustrated includes a base casting 1 having an upstanding wall 2 which is provided with a partition 3 having an aperture 4 in the same. The outer surface of the upper end of the upstanding part 2 is rabbeted at 5 to form a shoulder for supporting the heater.

An oil burner is designated conventionally at 6 and may be of any type of burner as desired. As the burner forms no part of the present invention it is not illustrated or described in detail.

The contour of the heater is illustrated as cylindrical. However, the invention is susceptible of use with a heater of any contour or shape.

The combustion chamber A is defined by a shell designated generally as B and fashioned from sheet metal. The shell B is provided with a plurality of surfaces or fillets 7 and a plurality of what are termed herein as "plaits" 8. The plaits are formed from the metal of which the shell B is constructed by being deformed out of the plane thereof and consists of two sides 9 and 10 which are connected at the outer margin by a fold 11 and which opens into the interior of the combustion chamber A. The openings of the various plaits 8 into the combustion chamber A are herein designated as slots 12. The tops and bottoms of the surfaces 7 adjacent the slots 12 are secured together in closed formation as by spotwelding such closure being readily observed in Figures 1 and 3. The slots 12 are widened approximately intermediate the ends thereof adjacent the zone of greatest

heat within the combustion chamber A. In other words the plaits or slots 8 converge upwardly and downwardly from a central zone.

The partition 3 forms the lower end of the combustion chamber and the upper end thereof is formed by a top member 13 inserted in the upper end of the combustion chamber and secured in position as by spot welding or any other suitable manner.

10 The plaits 8 extend substantially radially from the combustion chamber A in the form of heater illustrated. The outer ends of these plaits 8 are surrounded by an outer casing 14.

15 There are formed between the plaits 8 the outer surface of the shell B and the inner surface of the casing 14 a plurality of pockets 15 which in the form of heater illustrated are vertically disposed. Through these 20 pockets 15 pass the heating medium such as air. The pockets 15 are open at the top and bottom so that air may freely pass through the same. The outer casing 14 is secured to the plaits 8 as by spotwelding or 25 welding of other character. The lower ends of the plaits are illustrated as cut on diagonal lines 16 which extend downwardly. The lower ends of the shell B rest on the shoulder 5 formed in the upstanding portion 2 of the base.

30 An outlet 17 is provided in one of the surfaces 7 of the inner shell B for communication with a stack 18 through which the products of combustion escape to the atmosphere.

35 The front of the base member is provided with a cover 19 within which pass the usual connections to the oil burner 6.

40 A line 20 in Figure 1 designates the approximate zone of greatest heat within the combustion chamber. This zone as will be observed is below the chimney outlet 17 and a considerable distance below the top of the combustion chamber.

45 Positioning the chimney outlet 17 below the top results in a zone above such outlet wherein the heat is retained for a considerable period of time after the oil burner has been shut off as is customary.

50 It is well recognized that oil burners and gas fired heaters operate intermittently so that for a time there is high temperature present in the combustion chamber and then when the fire is turned off the temperature falls. Such intermittent firing results in expansion and contraction of the parts of the heater to an extent which ordinarily eventually causes distortion or warping of such parts to the detriment of the heater.

55 The heater provided with the shell B of the present invention and the fins or plaits 8 lends itself readily to such expansion or contraction over a wide range without damage.

60 The operation of the heater is as follows: The oil burner 6 is fired whereupon heat

is generated within the combustion chamber A and radiated through the thin shell B and the fins 8 through the heating medium passing upwardly through the pockets 15, which medium in the present instance is air. The air enters the pockets at the lower end passing upwardly and thence outwardly through the open top for heating the surrounding atmosphere. It has been found that a heater 70 constructed in accordance with the present invention very readily heats a cold garage 75 in a short length of time such, for instance, as ten or fifteen minutes.

The oil burner continues in operation 80 whereupon the temperature within the combustion chamber rises causing expansion of the shell B i. e. fillets 7. Such expansion tends to close the slots 12 which movement is compensated for by the provision of the plaits 8 which tend to close during such expansion. 85 The provision of the intermediate widened portions of the slots allows greater expansion adjacent the zone of greatest or maximum temperature or heat without distortion or strain on the shell or the fins. When the oil burner is shut off the combustion chamber tends to cool, whereupon contraction of the 90 fillets 7 takes place and the parts return to normal position as shown in the drawing. 95 The alternate expansion and contraction due to intermittent firing sets up a bellows-like action or a breathing action within the combustion chamber and the plaits. Such action readily allows expansion and contraction to a marked degree without harm or damage to the shell B or the fins. The fins being constructed of light metal very readily radiate the heat within the combustion chamber to the heat conducting element such as air so 100 that the surrounding atmosphere is very quickly heated whenever the burner 6 is turned on for use.

Movement of the shell B and the fins 8 takes place transversely as well as longitudinally of the combustion chamber A. This is because of the fact that the upper and lower ends of the fins or plaits are closed. Consequently expansion of the shell B causes movement in the manner described. This movement is termed herein, for lack of better definition, as "breathing" or "bellows action".

110 It will be observed that a heater embodying the present invention is very simple and one which is adaptable to extreme high and low temperatures and one wherein this surrounding atmosphere is quickly heated when the fuel is fired.

115 A fire door is designated at 21 for access to the combustion chamber A. Utilization of the heater embodying the present invention and of the form illustrated would very quickly heat the surrounding atmosphere when the oil burner 6 is ignited as the heat generated within the combustion chamber A 120 125

is very quickly dissipated through the wall 7 and plaits 8 to the air passing upwardly through the pockets 15.

The invention is claimed as follows:

5 1. A heater combustion chamber comprising a plaited shell arranged with the plaits opening into the combustion space and with the portions of the shell defining the plaits convergent upwardly and downwardly from 10 a central zone.

15 2. A heater combustion chamber comprising a plaited shell arranged with the plaits opening into the combustion space and with the portions of the shell defining the plaits 15 convergent upwardly and downwardly from a central zone, the tops and the bottoms of the plaits being closed together.

20 3. A heater combustion chamber of substantially circular form comprising a shell formed with circumferentially separated plaits connected by fillets, the fillets defining the generally circular combustion space of the chamber, said plaits being open to the combustion space, the edges of the plaits being 25 convergent upwardly and downwardly from a central zone of maximum heat, the tops and bottoms of the plaits being closed together, the expansion and contraction of the fillets due to temperature variations setting up breathing actions in the plaits and 30 vertical movement in the shell.

35 4. A combustion chamber for a heater, said chamber comprising a shell of generally circular form in plan fashioned to provide plaits and fillets, the fillets spacing said plaits circumferentially and defining a central combustion zone and constituting the inner wall of the combustion chamber, the edges of the plaits diverging downwardly 40 from the top towards a zone of maximum heat and diverging upwardly from the bottom towards said zone, the expansion of the fillets causing movement of the edges of the plaits towards each other and the contraction 45 of the fillets causing movement of the edges of the plaits away from each other.

50 5. A combustion chamber for a heater, said chamber comprising a shell of generally circular form in plan fashioned to provide plaits and fillets, the fillets spacing said plaits circumferentially and defining a central combustion zone and constituting the inner wall of the combustion chamber, said plaits varying in width from top to bottom with the greatest width thereof near the 55 zone of maximum heat.

60 6. A combustion chamber for a heater, said chamber comprising a shell of generally circular form in plan fashioned to provide plaits and fillets, the fillets spacing said plaits circumferentially and defining a central combustion zone and constituting the inner wall of the combustion chamber, said plaits varying in width from top to bottom with the 65 greatest width thereof at substantially mid-

height of the chamber whereby maximum expansion and contraction may occur in the zone of maximum heat.

7. A heater combustion chamber comprising a plaited shell of substantially thin sheet metal arranged with the plaits opening into the combustion chamber, the plaits being spaced and connected by fillets, the fillets defining generally the combustion space of the chamber, the width of a fillet between two adjacent plaits being greater than the maximum opening of a plait, the plaits and fillets being so arranged that for a given space a maximum heating surface is presented to the heat zone within the combustion chamber, the plaits being convergent in a direction away from the combustion chamber with the side faces flat and slightly inclined to the direction of heat radiation whereby the radiant energy of the combustible fuel is absorbed by the plaits and passed on to the heating medium surrounding said combustion chamber.

In testimony whereof I have hereunto subscribed my name at Chicago, Cook County, Illinois.

ROY I. MILLS.
